UNITED STATES PATENT OFFICE

CESARE C. CAMPUS, OF SANTA MONICA, CALIFORNIA

SANITARY FITTING

Application filed April 28, 1930. Serial No. 448,046.

The purpose of my invention is to provide an attachment to a water closet apparatus incorporating a bidet nozzle by means of which with its associated parts a stream of water can be projected upon the posterior portion of a person occupying said water closet. Various types of bidet nozzles have been devised but so far as known to your petitioner all have had the great disadvantage of spilling the water when the seat is not occupied, provided that the bidet valve should be left open or opened intentionally. This condition is due to the bidet nozzles heretofore designed being mounted at such an angle in relation to the closet bowl that in most cases the jet is directed in either a horizontal or upwardly direction. When the seat is not occupied there is no obstruction to the jet and the water is consequently spilled outside the bowl. The non-spilling of the water depended on the closing of the water supply valve and there being no means of preventing this careless or mischievous opening of the valve, damage naturally resulted and consequent discrediting of this sanitary and practical device.

The further purpose of my invention is to provide a bidet nozzle arrangement which will eliminate the possibility of the water discharging outside the bowl, and also to provide such a design of bidet that the same can be applied to bowls already installed. In the case of new bowls means are provided for raising the jet so that it will be a more efficient cleanser. A particular feature of my invention is the fixation of the said bidet nozzle, preventing any swinging motion whether the seat is raised or in position for use.

40 I accomplish these objects by means of the construction shown in the accompanying drawings, in which similar figures refer to similar parts in the several views.

Figure 1 is a plan view partly in section with the seat in its normal position for occupancy. Figure 2 is a vertical central section taken on the line X—X of Figure 1; also showing the seat in its normal lowered position. Figure 3 is a vertical central section taken on the line X—X of Figure 1

but with the seat in its raised position. Figure 4 is a plan view partly in section of a modified form of my invention also showing a recess in the inside of the front rim of the bowl. Figure 5 is a vertical central section taken on line Y—Y of Figure 4. This figure also shows the recess in the interior front rim of the bowl. Figure 6 is a side elevation of the bowl and bidet with the seat in its raised position, and also showing a section of the front rim of the bowl in which a hole is provided for the reception of the water stream from the bidet nozzle.

The construction of my device as shown in Figures 1 to 3 inclusive is as follows:— 65 10 is a water closet bowl of the usual construction, having a hollow rim 11, and a seat attachment flange 12 at either side of the rear portion of the bowl. The seat wings 13 are of the usual construction and provided 70 with hinge brackets 14 integral with the transverse bracket 15 for the purpose of joining the two seat wings so as to operate as one unit. The hinge brackets 14 and the transverse bracket 15 are revolvably or 75 hingedly mounted on the bearings 16 and 17 as more fully described hereinafter. Detachably secured to the rearwardly projecting flanges 12 are two hinge and bidet supports 18 and 19. In the construction as 80 shown in Figures 1 to 3 inclusive, the upper portion of the support 18 has a socket 20 adapted to receive the trunnion 21 which has its opposite end screwed or otherwise secured to the bidet supply chamber 22. That portion of the said trunnion 21 between the socket 20 and the chamber 22 forms a support for the bearing 16. Mounted in the support 19 is a water supply pipe 23 which is connected at its exterior end to a suitable 90 source of supply and is provided with means of control such as the water valve 24. The interior end of the pipe 23 passes through the support 19 and is screwed or otherwise secured to the said bidet supply chamber 95 22. The space on the said pipe 23 between the support 19 and the chamber 23 forms a bearing for the hinge 17.

The bidet nozzle 25 is integral with or secured to the bidet supply chamber 22 in 100

such a manner that the stream issuing from said nozzle will be projected in a slightly downwardly direction and strike the inside of the front of the bowl just below the rim 11. The nozzle 25 is preferably made to project into the said supply chamber 22 providing a long tube of relatively small diameter for the purpose of confining the issuing stream to a narrow angle instead of a wide 10 angled conical spray. Particular attention is directed to the fact that the bidet nozzle is not raised in any degree when the seat is raised. The trunnion 21, the pipe 23 and the chamber 22 are all stationary but the bracket 15 together with the hinge bearings 16 and 17 rotate about the axis of the said trunnion and pipe.

In the modified form shown in Figures 4 to 6 inclusive the bowl 10 is provided with 20 the rearwardly and laterally projecting flanges 12, but the rim 11 is so moulded as to form a pocket 30 for the reception of the jet 31 as particularly shown in Figures 4 and 5. This is for the double purpose of 25 enabling the line of the jet 31 to be raised to a higher position at the rear of the bowl so that the stream of water is more certain of striking the body as intended. This pocket 30 also prevents the splashing of the water. 30 Figure 6 shows an alternative design in which the rim 30 is provided with a passage 32 for the jet to enter, thus entirely preventing any possibility of splashing. The wings of the seat 13 are bifurcated and connected 35 together by the hinge bracket 33 the said bracket having the two hinges 34. These hinges 34 are rotatably mounted on the hollow pindle 35, one end of which is trunnioned in the seat attachment 36 and the opposite 40 end trunnioned in the seat attachment 37 by means of the water supply pipe 38. Centrally located on the hollow pindle 35 is a transverse chamber 39 which together with the pindle 35 is stationary and can be registered to a downwardly inclined position as 45 shown. The bidet nozzle 40 is tubular and preferably screwed into the chamber 39 and is made relatively long with a small central passage for the purpose of confining the 50 stream of water to a narrow jet shooting centrally across the bowl. 41 is a notch in the hinge bracket 33 located opposite the nozzle 40 and is provided so that the seat can be raised without interference with the jet. 55 If desired a passage can be provided instead of the notch 41 for the same purpose.

From the foregoing description it will be seen that the purpose of my invention has been accomplished by the device as shown 60 and that the stationary, downwardly inclined bidet nozzle and splash preventing means entirely preclude the spilling of water outside the bowl and at the same time avoid the possibility of injury to the clothing of the user. We obtain these desirable

results without complication or special attachments.

What I claim as my invention and desire to secure by Letters Patent is:—

1. The combination with a closest bowl 70 and a seat therefor, of a bidet nozzle having its orifice located above the under surface of the seat with the nozzle so situated as to project a stream discharging downwardly in relation to the bowl and below the rim 75 thereof.

2. The combination with a closest bowl having a rim at its upper edge and a seat therefor of a bidet nozzle mounted on the rear portion of the bowl having its orifice 80 located between the planes of the upper and lower surfaces of the seat, with the nozzle so placed as to project a stream, discharging downwardly, in relation to the bowl, and under the rim thereof at the front of the 85 bowl.

3. The combination of a closest bowl, a seat consisting of two elements held together by a fixture hingedly mounted on a hollow pindle, said pindle being secured to said 90 closest bowl and also connected to a controllable source of water supply; a nozzle having its posterior end inserted in and open to the hollow passage in said pindle and having its outer end so located as to discharge a 95 stream downwardly between the two elements forming the seat, said stream being directed to a point below the front rim of the bowl whenever said water control is open.

4. The combination of a closest bowl, a 100 seat consisting of two elements held together by a fixture hingedly mounted on a hollow pindle, said pindle being secured to said closest bowl and also connected to a controllable source of water supply; a rearwardly 105 extending hollow chamber connecting with said pindle and said hollow chamber thereof, a nozzle inserted in said pindle having its posterior end extending rearwardly into said hollow chamber, said chamber and said nozzle being so located as to direct a stream 110 downwardly between the two seat elements toward a point below the front rim of the said bowl; and an opening in said hinge fixture adapted to register with the front opening of said nozzle when seat is in its downward position.

5. The combination of a closest bowl having mounted thereon a hollow pindle adapted 120 to be connected to a source of water supply, a nozzle transversely and centrally located in said pindle and connecting with the hollow interior thereof; a seat consisting of two elements connected by a plate, said plate being hingedly mounted on said pindle and having an opening therein so located that when said seat is in its downward position 125 a stream from said nozzle can pass through said opening in a downwardly direction to 130

ward a point through or under the front rim of said bowl.

6. In combination with a closest bowl having an inwardly extending rim about the opening therein, a swinging seat mounted on said bowl, and a bidet nozzle mounted on the rear portion of the bowl, angularly disposed to discharge a stream of water downwardly to impinge on the front portion of the bowl under the rim.

10 7. In combination with a closet bowl having a seat, and a bidet nozzle mounted on the rear portion of said bowl, said nozzle being angularly mounted on the bowl to discharge a stream of water forwardly and downwardly below the top of the bowl.

15 8. In combination with a closest bowl having a rim about the opening therein, said rim having an opening therein at the front portion of the bowl, a bidet nozzle mounted on the rear portion of the bowl angularly disposed to direct a stream of water into the opening in the rim.

20 9. In combination with a closet bowl having a rim about the opening therein, said rim having a pocket therein at the front portion of the bowl, a bidet nozzle mounted on the rear portion of the bowl angularly disposed to direct a stream of water into the opening in the rim.

25 10. In combination with a closest bowl, a seat swingingly mounted thereon, said seat having two wings connected at the rear end thereof, and a bidet nozzle angularly mounted on the bowl arranged to discharge a stream of water downwardly and forwardly between said wings into the bowls.

30 11. In combination with a closet bowl having a seat, a bidet nozzle mounted on the rear portion of the bowl angularly disposed with relation to the upper surface of the bowl to discharge a stream of water forwardly and downwardly through an opening in the back of said seat and against the front inner surface of the bowl.

35 12. The combination of a closet bowl having mounted thereon a hollow pintle adapted to be connected to a source of water supply; a rearwardly extending hollow chamber connecting with said pintle and the hollow chamber thereof; and a nozzle inserted in said pintle having its posterior end extending rearwardly into said hollow chamber, said chamber and said nozzle being so located as to direct a stream downwardly into said bowl toward a point below the front rim of said bowl.
